FLUID FEEDING APPARATUS

Arthur E. McFarland, Houston, Tex.

Application June 14, 1950, Serial No. 168,030

4 Claims. (Cl. 103—37)

1

This invention relates to fluid feeding apparatus, and more particularly to mechanism for delivering a treating fluid in controlled quantity to a desired point of use.

The invention is capable of broad application wherever the delivery of fluids is desirable, and is especially adaptable for use in the continuous feeding of treating fluid in accurately regulated quantities to a flowing liquid to be treated, such as oil or water.

An important object of the invention is to provide fluid feeding apparatus which is capable of use with fluids of widely varying viscosity and which is readily adjustable to accurately regulate the quantity of fluid delivered over a given period of time.

Another object of the invention is the provision of fluid feeding apparatus having fluid pumping mechanism operable by a reciprocating part having a constant length of movement, and including means for varying the amount of fluid displaced.

A further object of the invention is to provide fluid feeding apparatus having fluid pumping mechanism, which includes a reciprocating member having a passageway therethrough, through which fluid is admitted to the pump cylinder and valve means cooperable with the reciprocating member to open and close the passageway, the valve means being adjustable to limit the opening and closing of the passageway.

The invention also contemplates the provision of means for varying the capacity of the pump cylinder in a fluid feeding apparatus of the type referred to.

Another object of the invention is to provide fluid feeding apparatus having a motor of novel construction for driving the same, and by which a member of fluid feeding pumps of such apparatus may be simultaneously operated.

A further object of the invention is to provide fluid feeding apparatus which includes a fluid operated motor having a novel system of lubrication, and which is of simple construction capable of being easily dismantled for purposes of maintenance and repair.

A still further object of the invention is the provision of fluid feeding apparatus of simple design and rugged construction, having few operating parts, and capable of long continued operation under the extreme conditions of hard usage and exposure to which such equipment is likely to be subjected.

The invention will best be understood from the following detailed description of a preferred

2

embodiment of the same, when taken in conjunction with the annexed drawings, wherein:

Figure 1 is a top plan view showing the fluid pumping mechanism of the invention and illustrating the manner in which it is associated with the motive means and source of fluid supply;

Figure 2 is a cross sectional view taken along line 2—2 of Figure 1;

Figure 3 is a vertical, central cross-sectional view of the motor of the fluid feeding apparatus, showing how the pump mechanism is attached to and operated thereby;

Figure 4 is a horizontal cross-sectional view taken along line 4—4 of Figure 3, and

Figure 5 is a horizontal cross-sectional view taken along the line 5—5 of Figure 3.

Referring now to the drawings in greater detail, the invention is shown on Figures 1 and 2 applied to a reciprocating piston type of fluid operated pump or motor indicated generally at 2 which motor includes a cylinder 4, wherein a piston 6 is adapted to reciprocate. The motor also has a cylinder head 8 to which the chemical feeding mechanism of the invention may conveniently be attached.

The chemical feeding or injector mechanism comprises a generally cylindrical casing 10, supported on the cylinder head 8, which casing may include a pump cylinder 12 wherein a pump plunger 14 operates. The casing 10 is fitted at its inner end upon a support member 16 having a threaded projection 18 which extends through a central opening in the cylinder head 8 and is secured thereto by a nut 20. A connecting rod 22 attached in any suitable manner to the piston 6 and moveable therewith passes through a central opening in the support member 16, and is surrounded by suitable packing 24 disposed in a stuffing box 26 therein in which the packing 40 is compressed by a gland 28.

The pump plunger 14 is attached to the outer end of the connecting rod 22, as by threading, and passes through a plug 30 located in the casing, and having suitable packing 32 disposed in a stuffing box 34 in the plug which is provided with a gland 36. The pump cylinder 12 has a reduced end portion 44 which fits into the outer end of the casing 10, and the plunger 14 passes into the pump cylinder through packing 38 located in a stuffing box 40 and compressed therein by a gland 42. A suitable opening, such as that indicated at 43 may be provided in the casing 10 through which the glands 28 and 36 may conveniently be adjusted.

The support member 16, plug 30 and portion

44 of the pump cylinder may all be secured to the casing in any convenient manner, such as by press fitting these parts into the casing, in which case packing elements 46 may be provided to assure a fluid tight seal between the parts. The parts may, of course, be secured in the casing in any other suitable manner.

There is a chamber 48 in the pump cylinder which opens into an enlarged bore 50 at the outer end of the cylinder, and the chamber 48 is 10 threaded interiorly for the reception of an exteriorly threaded hollow liner 52, which is adjustable in the chamber. An enlarged portion 54 on the liner moves in the enlarged bore 50 and carries the packing 56 thereon to form a fluid 15 tight seal between the liner and the cylinder. At its outer end the liner is provided with a head 58 by which the liner may be adjusted in the cylinder.

The liner has a hollow cylindrical bore 60 20 therein, within which a pointed valve body 62 is moveably disposed. A fluid passageway 64 is provided in the pump plunger 14, which passageway opens outwardly at one end through the side of the plunger mediate the ends thereof, and at the other end communicates with a tapered seat 66 formed on the free end of the plunger. The plunger extends through the inner end of the liner 52 through an opening 53 which is of substantially greater diameter than the diameter of the plunger, so that fluid may flow freely into 25 and out of the bore 60 about the plunger.

The valve 62 is urged into engagement with the seat 66 on the plunger by a coil spring 68, and the valve is of substantially smaller diameter than the cylindrical bore 60 of the hollow liner so that fluid may flow freely past the valve as the same reciprocates in the liner.

The plug 30 and the inner portion 44 of the pump cylinder are spaced apart within the casing 10 to form a fluid feed chamber 70 therein, which is in communication by way of a feed pipe 72 with a source of supply, such as the storage tank indicated at 73. A suitable hand valve 74 may be inserted in the feed pipe 72 to control the flow of fluid from the supply source, and a sight gauge 76 may also be provided for visual observation of the flow of the fluid.

The feed chamber 70 communicates with the pump chamber 48, by a pipe 78, in which a check valve 80 is located to prevent back flow of fluid from the chamber 48 to the feed chamber 70. A discharge pipe 82 also opens into the pump chamber 48 and is provided with a check valve 84 which prevents back flow of fluid from the discharge pipe into the pump chamber.

In making use of the invention, the discharge pipe 82 is connected to any desired location where fluid is to be fed and the hand valve 74 is opened to allow fluid from the supply tank 73 to pass through the supply line 72 into the feed chamber 70. The pump plunger 14 is then reciprocated by operation of the motor M.

In the condition of the mechanism illustrated in Figure 2, the pump plunger is at the end of its pumping stroke and the passageway 64 is closed by the valve 62. When the plunger moves to the left, toward the motor, the valve 62 follows the plunger under the influence of the spring 68, and keeps the passageway closed until the valve engages the end of the liner 52. Further movement of the plunger to the left, after the valve has been stopped by engagement with the end of the liner, opens the passageway 64 and establishes communication therethrough between the feed cham-

ber 70 and the pump chamber 48, whereupon fluid enters the pump chamber to replace the fluid previously discharged therefrom.

The pump plunger is then again moved to the right and upon engagement of the seat 66 with the valve 62, the passageway 64 is closed off. Further movement of the plunger to the right then results in opening the valve 84 to discharge a portion of the fluid from the pump chamber.

By screwing the liner 52 into or out of the cylinder the size of the chamber 48 and the point of opening of the passageway 64 can be adjusted very accurately to control the exact amount of fluid which is discharged at each pumping stroke of the plunger.

When large amounts of fluid are to be delivered to the desired point, the size of the chamber 48 may be increased by screwing the liner 52 further out of the cylinder and in this case the valve 80 in the pipe 78 will be inserted upon an intake stroke of the pump plunger to permit a larger amount of fluid to pass from the feed chamber 70 to the pump chamber 48.

Due to the fact that the valve 62 is of substantially smaller diameter than the cylindrical bore 60 of the liner 52 fluid may flow freely past the valve as it reciprocates and the liner will therefore be entirely filled with fluid during the operation of the apparatus. After the valve has engaged the seat 66 of the plunger 14, further movement of the plunger into the pump cylinder will cause displacement of the fluid from the pump chamber 48. Movement of the plunger out of the cylinder with the valve seated thereon results in increasing the volume in the cylinder, so that when the valve is unseated by engagement with the end of the liner fluid is quickly drawn into the pump chamber from the feed chamber 70 through the passageway 64 of the plunger.

It will be noted that the passageway 64 is in open communication with the feed chamber 70 and the pump chamber 48 during movement of the plunger into the pump cylinder, so that fluid may return from the pump chamber to the feed chamber until the valve 62 is seated and closes the passageway, after which further movement of the plunger into the cylinder results in displacement of a portion of the fluid therefrom. By this construction it is possible to secure very accurate adjustment of the amount of fluid which is pumped, by adjusting the distance to which the liner 52 extends into the pump cylinder.

The operating motor of the fluid feeding apparatus has the preferred construction illustrated in Figures 3 and 4 of the drawings, wherein the motor is generally indicated at 2 as provided with a plurality of cylinder 4, in this case four in number, in which pistons 6 are adapted to reciprocate. Each of the cylinders is closed by a cylinder head 8.

The cylinders 4 are connected in pairs by connecting rods 90 which are formed with elongated slots 92 mediate their ends, for the reception of roller bearings 94 positioned on the crank 96 of the crank shaft 98 which is rotatably supported in the ball bearing 100.

At its upper end the crank shaft 98 extends into a valve chamber 102, within a housing 104 secured to the top of the motor in any suitable manner. A passage 106 extends from the valve chamber 102 to each of the cylinders 4 for the admission of operating fluid to the cylinders and the same passage 106 also serves to exhaust the

fluid from each cylinder back to the valve chamber. An exhaust passage 110 also extends from the valve chamber and opens into the crank case of the motor about the crank shaft 98.

Within the valve chamber a valve 112 is secured to the upper end of the crank shaft 98 for rotation therewith. The valve 112 is seated on the top surface of the motor and has an inlet port 114 which registers successively with the passages 106 to admit fluid pressure from valve 10 chamber above the valve to each of the cylinders in turn. The valve also has a port 116 which is brought successively into registry with the passages 106 and 110 from each of the cylinders to permit the flow of fluid from the cylinders into the crank case of the motor, whence it may pass out through a vertically disposed exhaust pipe 118 opening at its lower end into the crank case or chamber 119, as seen in Figure 4.

A pipe 120 leads from a source of fluid supply, under the control of fluid pressure regulating means not shown, into the top of the valve chamber 102.

One of the pistons 6, as seen in Figure 3, is connected to a plunger 122 which extends outwardly through the cylinder head, and into the cylinder 124, of an oil pump 126, which is threadably secured to the cylinder head. Packing 128 of suitable character is disposed about the plunger 122 where the same enters the oil pump.

The oil pump has oppositely disposed fittings 130 and 132, respectively, attached thereto by which an oil intake pipe 138 and an oil outlet pipe 140 are respectively attached in communication with the cylinder 124. Check valves 134 and 136 are disposed in the fittings 130 and 132, respectively, whereby oil may flow in one direction through the pump but is prevented from flowing therethrough in the opposite direction. Oil inlet pipe 138 leads from the bottom of the crank case of the motor to the oil pump, and oil outlet pipe 14 leads from the oil pump to the valve chamber 102, so that when the motor is operating the oil is circulated from the crank case to the valve chamber, and thence back to the crank case.

It will be seen that the motor as described above may be operated by the application of pressure fluid through the pipe 120 to the valve chamber. The fluid will be admitted through port 114 to the passage 106 of each cylinder successively as the valve rotates, while at the same time the cylinder to which fluid was previously admitted is opened to exhaust the fluid through passage 106, valve port 116 and passage 110 leading into the crank case 119, when the fluid passes out of the exhaust pipe 118.

As the motor is operated the oil pump plunger 122 is reciprocated and when the plunger moves into the oil pump cylinder 124 the valve 136 is unseated, while valve 134 remains seated, which results in forcing oil out through the outlet pipe 140, and into the valve chamber 102. From the valve chamber the oil leaks past the valve 112 and through exhaust passage 110 into the crank case. Oil may also pass through passages 106 to each of the cylinders 4 where it serves to lubricate the pistons 6, and leaks past the same into the crank case or chamber 119.

As the oil pump plunger moves out of the cylinder 124 valve 134 is unseated while valve 136 remains closed, and oil is drawn in through inlet pipe 138 from the crank case 119 into the cylinder 124. Due to the pressure of the operat-

ing fluid in the valve chamber 102, and the flow of operating fluid through the intake port 114 and passages 106, as well as the flow of fluid out through the exhaust passage 110, into the crank case, the oil pumped into the valve chamber is forcibly circulated through the working parts of the motor to thoroughly lubricate the same, thus increasing the life of the motor and improving the ease and smoothness of its operation.

The connecting rod 22 of the fluid feeding pump mechanism is attached to one of the pistons 4 for reciprocation therewith in the manner previously described, and it will be apparent that a similar pumping mechanism can be applied to three of the pistons of the motor if desired, while the fourth piston operates the oil pump.

From the above description of the construction and operation of the invention it will be seen that the same provides a simple and easily manufactured fluid feeding apparatus, which is readily adaptable for use with a wide variety of treating fluids, whereby such fluids may be continuously delivered in any desired quantity to a point of use.

While the invention has been disclosed in connection with a specific embodiment thereof, it will be understood that the same is by way of example only, and many changes in the construction and arrangement of the various parts can be made without departing from the spirit of the invention and within the scope of the appended claims.

Having thus clearly shown and described the invention, what is claimed as new and desired to secure by Letters Patent is:

1. In fluid dispensing apparatus, a fluid pump comprising a casing having a fluid feeding chamber connected to a source of fluid supply, said casing having a fluid pumping chamber, a plunger reciprocable in said chambers, said plunger having a passageway therein with an opening at one end in communication with said feeding chamber and a valve seat at the other end of said passageway in said pumping chamber, a valve in said pumping chamber engageable with said valve seat to close said passageway, yieldable means in said pumping chamber urging said valve in closing direction, and means in said pumping chamber engageable by said valve upon movement of said plunger outwardly of said pumping chamber to unseat said valve.
2. In fluid dispensing apparatus, a fluid pump comprising a casing having a fluid pumping chamber, said chamber having a discharge outlet, valve means in said outlet, a plunger moveable inwardly and outwardly of said chamber, said plunger having a passageway therein with an opening in communication with a source of fluid supply outside said chamber and a valve seat in said passageway within said chamber, a valve moveable in said chamber and engageable with said valve seat upon movement of said plunger inwardly of said chamber to close said passageway, yieldable means in said chamber urging said valve in closing direction, and means in said chamber for varying the amount of fluid discharged by the pump including stop means engageable by said valve to limit closing movement of said valve and means for adjusting the position of said stop means in said chamber.
3. In fluid dispensing apparatus, a fluid pump comprising a casing having a fluid pumping chamber, said chamber having a discharge out-

let, valve means controlling the flow of fluid through said outlet, a plunger moveable inwardly and outwardly in said chamber, said plunger having a passageway therein with an opening in communication with a source of fluid supply outside said chamber, and a valve seat in said passageway within said chamber, a sleeve adjustably supported in said chamber, said plunger extending into said sleeve, a valve moveable in said sleeve and engageable with said valve seat upon movement of said plunger inwardly of said chamber to close said passageway, yieldable means in said sleeve urging said valve in closing direction, said valve being engageable with said sleeve to limit movement of the valve in closing direction upon movement of said plunger outwardly of said chamber, to open said passageway.

4. In fluid dispensing apparatus, a fluid pump comprising a casing having a fluid pumping chamber, said chamber having a discharge outlet, valve means controlling the flow of fluid through said outlet, a plunger moveable inwardly and outwardly in said chamber, said plunger having a passageway therein with an opening at one end thereof in communication with a source of fluid supply and a valve seat at the other end of

10

said passageway within said chamber, a valve moveably disposed in said chamber and engageable with said seat upon movement of said plunger inwardly of said chamber to close said passageway, resilient means in said chamber urging said valve in closing direction, means moveable longitudinally in said chamber for varying the fluid capacity of said pump, said means being engageable by said valve upon movement of said plunger outwardly of said chamber to limit movement of the valve in closing direction to open said passageway.

ARTHUR E. McFARLAND.
